UNITED STATES PATENT OFFICE.

THOMAS ALLATT, OF WESTFIELD, NEW JERSEY, ASSIGNOR, BY MESNE ASSIGNMENTS,
TO MILLIE PATENT HOLDING CO., INC., OF NEW YORK, N. Y., A CORPORATION OF
NEW YORK.

TAG.

Application filed January 29, 1923. Serial No. 615,663.

To all whom it may concern:

Be it known that I, THOMAS ALLATT, a subject of the King of Great Britain, and resident of Westfield, in the county of Union 5 and State of New Jersey, have invented certain new and useful Improvements in Tags, of which the following is a specification.

The present invention relates to improvements in tags, particularly designed for use 10 on merchandise, said tags serving to receive descriptive matter. The invention pertains more particularly to that type of tags, which is attached to one end of a string, the other end of the latter being secured to the mer- 15 chandise.

The main object of the present invention is to provide a simple and inexpensive means for securely fastening the string to the tag, said means being so constructed that the 20 fastening operation may be effected by machinery.

With these and other objects in view, which will more fully appear as the nature 25 of the invention is better understood, the same consists in the combination, arrangement and construction of parts hereinafter described, pointed out in the appended claim and illustrated in the accompanying drawings, it being understood that many 30 changes may be made in the size and proportion of the several parts and details of construction within the scope of the appended claim, without departing from the spirit or sacrificing any of the advantages 35 of the invention.

One of the many possible embodiments of the invention is illustrated in the accompanying drawings, in which:—

Figure 1 is a plan view of a tag constructed in accordance with the present invention; Fig. 2 is an inverted plan view thereof; Fig. 3 is a section taken on line 3—3 of Fig. 1, on a larger scale; Fig. 4 is a perspective view of the attaching means, also on a larger scale; and Fig. 5 is a diagrammatic view, partly in section, of a simple mechanism for uniting the elements of the tag.

In the drawings, the numeral 10 indicates 50 a tag, which may be of any suitable material, preferably of cardboard, of any desired size. To this tag is fastened by a

staple 11 a string 12, said staple being U-shaped, as clearly shown in Fig. 4 of the drawings. The staple comprises a body portion 13, which is disposed flat against one face of the tag, and two prongs 13, which are extended through and then bent toward the opposite face of the said tag, clamping the string 12 against the said opposite tag 55 face. The prongs are so shaped that they lay side by side, when bent against the tag, in overlapping positions, at least one of the prongs being passed through the string, as clearly shown in Figs. 2 and 3 60 of the drawings. The purpose of passing at least one of the prongs through the string is to prevent the latter from being disengaged from the tag. The prongs are disposed side by side, so as not to project 65 70 too far beyond the tag face, and they overlap to embrace the tag in any position of the string on the tag.

In Fig. 5 of the drawings a simple mechanism is diagrammatically illustrated for 75 uniting the elements of the tag. This mechanism comprises a base 15, in which is formed a recess 16, constituting the female uniting die, the male die being represented by a plunger 17, which moves between 80 guides 18. The string 12 is first extended through the recess 16, and the tag 10 placed upon the base 15, the staple 11 being then inserted between the guides 18, after which the plunger 17 is driven downwards, whereby the prongs 14 of the staple first penetrate the tag, they being then deflected by the recess 16, at least one of the prongs passing through the string, as experiments have 85 90 shown.

What I claim is:—

A device of the character described, comprising a tag, a string placed against one of the faces thereof, and a staple driven from the opposite face of the tag through the latter, said staple including two prongs bent against the tag in overlapping positions and clamping said string against said tag, at least one of said prongs passing through said string. 95 100

Signed at New York, in the county of New York and State of New York, this 18th day of December, A. D. 1922.

THOMAS ALLATT.
